UNITED STATES PATENT OFFICE

EFFIE LEE McMICHAEL, OF HOT SPRINGS, ARKANSAS

PORTABLE KITCHENETTE

Application filed November 2, 1928. Serial No. 316,805.

The present invention relates to an apparatus in the form of a kitchenette, in which the various parts necessary for the operation and maintenance of the ordinary kitchen are so supported and correlated that they form a foldable and expandible device capable of being opened and expanded or closed into a compact and convenient form for portability.

10 A still further very important object of the invention resides in the provision of a kitchenette of this nature which is exceedingly simple in its construction, strong and durable, easy to manipulate, thoroughly efficient and reliable in use and otherwise well adapted to the purpose for which it is designed.

With the above and numerous other objects in view as will appear as the description 20 proceeds, the invention resides in certain novel features of construction, and in the combination and arrangement of parts as will be hereinafter more fully described and claimed.

25 In the drawing:

Figure 1 is a perspective view of the kitchenette embodying the features of my invention showing the same folded to a closed position,

30 Figure 2 is an elevation thereof showing the same extended to an open position with the combined table and door removed,

Figure 3 is a vertical section through the apparatus when folded,

35 Figure 4 is an enlarged detail section through one section of the cabinet showing the means for swinging the combined door and table to an open position,

40 Figure 5 is an enlarged detail section taken substantially on the line 5—5 of Figure 3,

Figure 6 is a vertical detail section through the refrigerating portion of one of the sections,

45 Figure 7 is an enlarged detail section taken substantially on the line 7—7 of Figure 3,

Figure 8 is an enlarged detail horizontal section showing the hinge connection for the combined table and door with its cabinet section,

50 Figure 9 is a side elevation of the combined

table and door in an extended position ready for use,

Figure 10 is a transverse vertical section therethrough,

Figure 11 is an enlarged detail section 55 taken substantially on the line 11—11 of Figure 3, and

Figure 12 is an enlarged detail section taken substantially on the line 12—12 of Figure 2.

Referring to the drawing in detail, it will be seen that this kitchenette apparatus comprises two sections A and B hingedly connected together as at 5 so that the sections may be closed and fastened together by suitable fastening means 6 as is indicated in Figure 1 or so that they may be unfolded to the extended position shown in Figure 2 so as to permit access to the interior of the cabinet section.

Each section includes a bottom 7, side walls 8 and 9 rigidly rising from the ends thereof and a rear wall 10 rigidly rising from the rear edge thereof and rigidly secured to the side walls. Top panels 11 are hingedly engaged as at 12 with the rear walls 10 to close the tops of the sections and these top panels are held in closed position by a hook and eye connection 14 with the side walls 9 and 8.

Partitions 15, 16 and 17 divide the section 80 A into four compartments. A hinged panel 18 closes the top compartment above the partition 15 being hinged as at 19 to said partition 15.

The panel 18 may be swung to a horizontal open position and held in such position by braces 20 formed of hinged links pivotally connected as at 21 to each other, pivotally connected as at 22 to the panel 18 and pivotally connected as at 23 with the sides of 85 the top compartment.

The top closed panels 11 are limited in their upward swinging movement by similarly constructed braces 24. The top compartment of the section A is lined with asbestos 25 and sheet metal 26 so that a stove may be stored therein and may be used by opening up the panel 11 and the panel 18.

A strap handle 27 is provided on the panel 18 so that the same may be readily opened. 100

Between the partitions 15 and 16 there is formed a compartment for slidably receiving a drawer 28 in which may be stored tea, coffee, sugar etc. This drawer has a strap handle 29 thereon so that it may be readily pulled open when desired.

In the next compartment between partitions 16 and 17 there is slidably mounted a drawer 30 with a strap handle 31 thereon. 10 This drawer is lined with cork 32 and zinc 33. A fixed panel 34 partially closes the rear of the drawer and has hinged thereto as at 35 a panel 36.

These panels 34 and 36 are similarly lined 15 to the rest of the drawer. The panel 36 may be swung to an open position when the drawer is open so that a cake of ice may be placed therein. The partition 17 is provided with an oblong slot 37 and the drain pipe 38 de- 20 pending from the bottom of the drawer 30 extends through this slot so that water from the ice may drip through the drain pipe into a receptacle 39 resting on cleats 40 in the upper portion of the lowermost compartment 25 of section A between partition 17 and the bottom 7.

The lowermost compartment has a pair of doors 40. These doors are hinged to the sides 8 and 9 as is indicated at 41 and have 30 strap handles 42 so that they may be opened.

In this lowermost compartment cooking utensils may be stored below the drip pan or receptacle 39 or the compartment may be used for any other suitable or desired pur- 35 pose.

In the other section B there are mounted partitions 43, 44 and 45. These partitions 43, 44 and 45 extend between the side walls 8 and 9 and the rear wall 10 of section B, 40 but unlike partitions 15, 16 and 17, these partitions 43, 44 and 45 terminate short of the edges of the sides 8 and 9 remote from the rear wall 10.

The partitions 43, 44 and 45 are spaced 45 from each other and the partition 43 is spaced from the top of the section B and the partition 45 is spaced from the bottom of section B. A drawer 46 having a strap handle 47 is slidable between partition 43 and 44 and this 50 drawer is designed particularly for storing knives, forks and spoons.

A drawer 48 is slidable between the partitions 44 and 45 and has a strap handle 49 and this drawer may be used for groceries, 55 table linens or for any other desired or suitable purpose.

In the compartment above the partition 43 there is mounted cross bars 50 on blocks 51. The sides 8 and 9 of the section B in this up- 60 per compartment have channels 52 in which are disposed springs 53 anchored as at 54 to the rear wall 10 and anchored as at 55 to the blocks 51 so as to draw the bars 50 toward the rear wall so that dishes and the like may 65 be tightly stored in a compact manner in

this upper compartment so as to prevent the breakage, rattling, and the like.

A suitable number of hooks 56 are mounted on the inner surfaces of the top portions of the side walls 8 and 9 in this section B so that 70 cups or the like may be hung thereon.

A plurality of benches 57 are stored in the bottom compartment below the partition 45 and includes foldable leg structures 58. These benches are held in place by a bar 59 75 extending between the side walls 8 and 9 and secured in place by hook and eye fasteners 60.

On all the drawers are used a spring pressed catch 61 shown clearly in Figure 12 so as to prevent the drawers from accidentally coming open. This spring pressed catch is slidable in a housing 62 with a spring 63 therein and the extremity thereof is adapted to engage in a keeper 64.

The letter C denotes generally a combined 85 table and door for the section B. This combined unit includes a panel 65 forming the door and the top of the table. This panel is provided with eye bolts 66 to receive pintle brackets 67 so that the unit may be hinged in 90 the cabinet section B, the bracket 67 being carried by the side 8, one at the top and one at the bottom thereof.

Obviously the panel 65 may be lifted so as to disengage the eye bolt from the pintle 95 bracket when it is desired to use the combined unit as a table.

Besides the panel, this combined unit includes leg sections each of which comprises a board 69 and legs 70. One of the boards 100 67 is hinged mounted as at 71 to a board 72 on the panel 65 while the other board 69 is hinged directly as at 73 to the panel 65.

This allows one leg structure to fold over the other leg structure in a compact rigid 105 manner as is indicated in Figure 3 which efficiently may be held by pivoted latches 74 on blocks 75 fixed to the panels 65.

As will be apparent from an inspection of the drawings the boards 69 are hinged 110 transversely of the panel 65. A pair of boards 76 are hinged as at 77 longitudinally of the panel 65 so that they may be disposed between the leg structure to hold them in an extended position or may be swung out of the 115 way as is clearly shown in Figure 11 to allow the leg structure to be folded.

A member 78 is pivotally mounted as at 79 on the side 9 of section D and a strap 80 is anchored thereto and anchored to the edge of said side 9 so that by pulling the strap, the member 78 may be swung to engage the panel 65 to open the same.

From the above detailed description it will be seen that I have devised an exceedingly 125 compact and convenient cabinet structure wherein there may be stored the essential requisites of a portable kitchenette so that the different units thereof are easily accessible when desired for use.

It will be seen that the structure is simple and may be manufactured strong and durable so as to be most efficient and reliable in use.

5 It is thought that the construction, utility and advantages of this invention will now be quite apparent to those skilled in this art without a more detailed description thereof.

The present embodiment of the invention 10 has been disclosed in considerable detail merely for the purposes of exemplification since in actual practice it attains the features of advantage enumerated as desirable in the statement of the invention and the above 15 description.

It will be apparent that changes in the details of construction, and in the combination and arrangement of parts may be resorted to without departing from the spirit or scope of 20 the invention as hereinafter claimed or sacrificing any of its advantages.

Having thus described my invention, what I claim as new is:

1. A vertically swingable cabinet section 25 having an open side, pintle brackets on one side wall adjacent the open side, a combination table and closure unit including a panel and foldable legs, eye bolts on the panel to pivotally and detachably engage the pintle brackets whereby said panel may function as 30 a door for the cabinet section or when detached the foldable legs when extended may be used as a table, and a pivoted latch on the panel for holding the legs in folded position.

35 2. A vertically swingable cabinet section having an open side, pintle brackets on one side wall adjacent the open side, a combination table and closure unit including a panel and foldable legs, eye bolts on the panel to pivotally and detachably engage the pintle brackets whereby said panel may function as 40 a door for the cabinet section or when detached the foldable legs when extended may be used as a table, a pivoted latch on the panel 45 for holding the legs in folded position, said panel provided with an opening, a swingable arm on the side wall engageable with the panel, and a strap projecting through said opening and secured to the inner end of the 50 arm whereby the panel may be partly opened.

In testimony whereof I affix my signature.

EFFIE LEE McMICHAEI.
